UNITED STATES PATENT OFFICE.

WILLIAM K. BLACK, OF PHILADELPHIA, PENNSYLVANIA, ASSIGNOR TO
JOSEPH HAWEY AND WILLIAM ADAMSON, OF SAME PLACE.

IMPROVEMENT IN CLAY PIPES AND APPARATUS FOR MOLDING THE SAME.

Specification forming part of Letters Patent No. 159,146, dated January 26, 1875; application filed December 21, 1874.

To all whom it may concern:

Be it known that I, WILLIAM K. BLACK, of Philadelphia, Pennsylvania, have invented certain Improvements in Clay Pipes and in Apparatus for Molding the same, of which the following is a specification:

The object of my invention is to so form the bell-mouth or socket of a drain-pipe as to reduce the risk of breakage, and so that a more perfect junction can be formed with the end of an adjoining pipe. These objects I attain by the peculiar apparatus for molding the pipe, in the manner which I will now proceed to describe, reference being had to the accompanying drawing, in which—

Figure 1 is a vertical section of the lower portion of the molding apparatus; Fig. 2, a sectional plan on the line 12, Fig. 1; and Fig. 3 a view of a modification.

A represents the clay-holding box of an ordinary drain-pipe machine, and B the former for the inside of the pipe, the lower end of this former being concentric with the opening in the bottom of the box, but less in diameter than the same, so that an annular space, x, intervenes between the two. D represents the former for the inside of a socket or bell mouth of the pipe, and E the former for the outside of the same. The formers D and E are fitted snugly to the under side of the former B and box A; but are readily removable from the same, for a purpose described hereafter. The former D has near the bottom an annular slotted flange, a, which is slightly curved upward, so as to impart a curved form to the end of the socket or bell-mouth of the pipe. To the former D are also attached three sets of pins, b, each set consisting, in the present instance, of four pins, which are beveled at their outer ends, as shown in Figs. 2 and 3. An annular rib, d, is formed upon the shoulder e of the former, the object of which is to form in that portion of the socket, against which the end of the adjoining pipe bears, a recess, d', for the reception of cement, thus aiding the formation of a tight joint.

The operation of the apparatus is as follows: Clay is forced down from the box A, by any suitable appliances, and into the space between the formers D and E. When this space is filled with clay the former D is turned round to the extent of one-third of a revolution, the effect of this movement being to

cause the pins b to make on the inner sides of the socket or bell-mouth four annular grooves, b', the beveled ends of the pins b pressing the clay, so as to form the grooves without tearing the clay. The formers D and E, and the body of clay contained between the same, are then lowered so that the clay, which is still fed down through the annular space x, forms the body of the pipe. When a pipe of the proper length has been molded it is removed from the formers D and E, and the operation is repeated.

In some cases it may be advisable to use movable pins, instead of using fixed pins, as above described, and in some instances I prefer the arrangement shown in Fig. 3, in which the spring-pins b may be advanced or retracted by means of a central conical plate, h.

The sockets of ordinary drain-pipes have the straight ends, as shown by dotted lines in Fig. 4, and these are apt to become fractured, as shown, when the pipe is roughly handled. By rounding the outer edges of the end of the socket, as shown at y in Fig. 5, no sharp corners are presented and the danger of fracture is much lessened.

The annular grooves formed in the inside of the socket afford a firm hold for the cement, which is used for the tight fitting of the two pipes together.

I claim as my invention—

1. The combination, in a clay-pipe molding-machine, of the former D, with three or more sets of pins, b, arranged and operating substantially in the manner and for the purpose described.

2. The combination, substantially as described, of the projection d and the slotted and curved flange a, with the former D, for the purpose set forth.

3. As a new article of manufacture a clay pipe, the socket of which has rounded ends y, internal grooves b', and an annular groove, d', in the shoulder, against which the end of the adjoining pipe bears, all as set forth.

In testimony whereof I have signed my names to this specification in the presence of two subscribing witnesses.

WM. K. BLACK.
